UNITED STATES PATENT OFFICE.

MARCUS BROCKWAY AND CHARLES N. WATTS, OF JAMESTOWN, N. Y.,
ASSIGNORS OF ONE-THIRD TO PORTER SHELDON, OF SAME PLACE.

APPARATUS FOR EXTINGUISHING FIRE IN RAILWAY-CARS.

SPECIFICATION forming part of Letters Patent No. 267,667, dated November 21, 1882.

Application filed June 28, 1882. (No model.)

To all whom it may concern:

Be it known that we, MARCUS BROCKWAY and CHARLES N. WATTS, of Jamestown, in the county of Chautauqua and State of New York, have invented new and useful Improvements in Apparatus for Extinguishing Fire in Railway-Cars, of which the following is a specification.

This invention has for its object to provide means whereby the fire in car-stoves can be quickly extinguished, in case of an accident to the train, to prevent the fire of the stove from igniting the surrounding wood-work of the car, and also to provide means whereby the lamps can be extinguished at the same time.

Our invention relates more particularly to a device in which the compressed air provided for operating the air-brakes is utilized in accomplishing these results; and our invention consists principally in combining with a car-stove a water-reservoir holding a sufficient quantity of water to extinguish the fire in the stove, and connected with the fire-pot of the stove by a suitable conduit, and to which air-pressure can be applied from the brake-pipe, so as to drive the water from the water-reservoir into the fire-pot of the stove when the fire is to be extinguished; also, in combining with the brake-pipe and water-reservoir an intermediate air-reservoir capable of holding a sufficient volume of air under pressure to drive the water from the reservoir into the stove; also, of mechanism whereby the air-pressure is applied automatically to the water-reservoir when the running-gear assumes an improper position with reference to the car-body—for instance, by one or more wheels leaving the rails; also, of mechanism whereby the air-pressure can be applied to the lamps so as to extinguish the light; and, finally, of various details of construction, as will be hereinafter fully set forth.

In the accompanying drawings, consisting of two sheets, Figure 1 represents a sectional elevation of our improved extinguisher. Fig. 2 is a sectional elevation of one end of a railway-car to which our improved extinguisher

is applied. Fig. 3 is a fragmentary cross section of the car.

Like letters of reference refer to like parts in the several figures.

A represents the floor of an ordinary railway-car; A' the roof, A² the sides, and A³ one of the ends, of the car.

B represents one of the trucks, of any ordinary construction, and b the pipe through which compressed air is supplied to the brake-cylinders in a well-known manner.

C represents the car-stove, and D a water-reservoir arranged near the stove and connected with the fire-pot thereof by a pipe or conduit, e. The latter connects with the lower end of the water-reservoir D, so as to permit all the water contained in the latter to be discharged through the pipe e into the fire-pot of the stove. The reservoir D is provided in its top with an opening, d, which is tightly closed by a removable screw-cap, d', or some other suitable device, and through which the reservoir can be filled with water. The reservoir is also provided with a water-gage, d², which renders the height of water in the same visible, and a faucet, d³, whereby the water can be drawn off, when necessary.

E represents an air-reservoir, arranged preferably below the water-chamber D, and connected with the brake-pipe b by a pipe, e. The latter is provided with a stop-cock, e', below the reservoir E.

f represents a check-valve, seated in the end of the pipe e within the reservoir E in such a manner that the valve will be lifted from its seat by the compressed air passing from the pipe into the reservoir, and will automatically seat itself and prevent the escape of the compressed air from the reservoir if the pipe e should become injured, so as to permit the escape of the air therefrom, or if the stop-cock e' should be inadvertently opened.

g represents a pipe which connects the air-reservoir E with the water-reservoir D, and which terminates in the latter above the water-level, to prevent the water from passing into the air-reservoir E and to deliver the air-pressure upon the surface of the water.

H is a three-way cock, arranged in the pipe g, between the reservoirs D and E, for controlling the admission of the compressed air from the air-reservoir E to the water-reservoir D.

- 5 I represents an air-pipe extending from the casing of the three-way cock H through the car, preferably near the roof thereof, and provided with branch pipes k, which open in a downward direction into the chimneys of the o lamps L, whereby the car is lighted, so that an air-current issuing from these branch pipes will reverse the air-current in the lamps and extinguish the lights. The principal passage m of the three-way cock H is designed to communicate with the two parts of the pipe g on opposite sides of the three-way cock, and the lateral passage n of the three-way cock is designed to communicate with the air-pipe I. In the normal position of the three-way cock H, which is represented in Fig. 1, the communication between the air-reservoir E and the water-reservoir D and the air-pipe I is broken, and the three-way cock may be held in this position by a suitable spring or weight, if necessary.

O represents an arm attached to the plug of the three-way cock, and p represents a rope or chain which extends from the end of the arm O downwardly through the car-floor and to the truck or running-gear, to which the chain is securely attached in such manner that the chain will permit all ordinary vibrations of the truck or running-gear without changing the position of the arm O, but that when the truck or running-gear changes its position with reference to the car-body considerably—as, for instance, when the running-gear leaves the track—such change of position in the running-gear or truck-frame will cause a pull on the chain p and draw the arm O downward until the plug of the three-way cock assumes a position in which the passages m and n of the three-way cock establish communication between the air-reservoir E and the water-reservoir D and pipe I.

In making up a train of cars provided with our improvement, the water-reservoirs D are first filled with water to the proper height and then tightly closed. After the cars have been coupled together and the compressed air has been admitted from the locomotive to the brake-pipe b, the stop-cocks e' are opened, whereby the reservoirs E are charged with compressed air under the pressure which exists in the brake-pipe. The pressure of the air is readily determined by pressure-gages, with which the air-reservoirs E may be provided. After the reservoirs E have been so charged, the stop-cocks are closed and the apparatus is ready for operation. If from any cause the truck or running-gear to which the chain p is secured should assume an abnormal position with reference to the car-body, the three-way cock H is opened, and the compressed air contained in the reservoir E is admitted to the reservoir D above the water-level, whereby the water is quickly forced out of the reservoir D through the pipe c and into

the fire-pot of the stove, whereby the fire is extinguished. A portion of the air contained in the reservoir E passes at the same time through the pipe I and its branch pipes k into the lamps, so as to extinguish the lights. In this manner the fire and lights are quickly extinguished in case of accident, and the danger of the cars taking fire from the stove or lamps is thereby avoided.

It is obvious that in case of danger the fire and the lights can be extinguished by simply pulling on the chain p, so as to open the three-way cock H.

We claim as our invention—

1. The combination, with a car-stove and a pipe or vessel containing compressed air, of a water-reservoir having its discharge-pipe connecting with car-stove, and means whereby the compressed air can be admitted to the water-reservoir, so as to force the water from the same into the stove for extinguishing the fire, substantially as set forth.

2. The combination, with a car-stove, a water-reservoir having its discharge-pipe connected with said stove, and a pipe or vessel containing air under pressure, of an air-reservoir adapted to receive and hold a sufficient volume of air to expel the water from the water-reservoir, and means whereby the compressed air can be admitted from said air-reservoir to the water-reservoir, substantially as set forth.

3. The combination, with a car-stove, a water-reservoir having its discharge-pipe connected with said stove, and a pipe or vessel containing air under pressure, of an air-reservoir adapted to hold a sufficient volume of air to expel the water from the water-reservoir, and means whereby the compressed air is automatically admitted to the water-reservoir when the truck or running-gear assumes an abnormal position with reference to the car-body, substantially as set forth.

4. The combination, with a car-lamp, of a vessel containing compressed air, a conduit leading from said vessel to the lamp, a valve whereby the flow of air from the vessel to the lamp is controlled, and means whereby the said valve is connected with the truck or running-gear of the car and whereby the air is automatically admitted to the lamp, so as to extinguish the light when the truck or running-gear assumes an abnormal position with reference to the car-body, substantially as set forth.

5. The combination, with a car-stove and the brake-pipe b, of an air-reservoir, E, water-reservoir D, connecting-pipe g, provided with a cock, H, water-discharge pipe c, and cord or rope p, whereby the cock H is connected with the running-gear or truck of the car, substantially as set forth.

6. The combination, with a car-stove and the brake-pipe b, of a water-reservoir, D, and an air-reservoir, E, connected with the brake-pipe by a pipe, e, having a stop-cock, e', and a valve, f, substantially as set forth.

7. The combination, in a railway-car, of the stove and one or more lamps with a pipe or vessel containing air under pressure, a water-reservoir, D, connected with the stove, an air-pipe, I, connecting with a lamp or lamps, and a three-way cock, H, whereby the compressed air can be admitted simultaneously to the water-reservoir and to the air-pipes leading to

the lamps, so as to extinguish the fire in the stove and the lights, substantially as set forth. 10
